FIG. 2A

VERY HIGH IMPEDANCE INPUT CIRCUIT

The present invention relates to electronic systems possessing a very high input impedance circuit; i.e., a circuit intended to prevent the system's own operation from disturbing the voltage signals delivered by a source to which the system is connected, for measurement purposes for example.

A well-known method of designing amplifier circuits utilizes negative feedback connected operational amplifiers. These amplifiers have a broad passband starting at zero and a very high negative open-loop gain. With a first negative feedback connected resistor and a second resistor connected to the amplifier input upstream of the connection point of the first, the open-loop gain of the amplifier is substantially equal to the ratio of the two resistances. To obtain a high input impedance, this second resistor may be given a very high value. However, one is limited in this regard particularly by the fact that the resistive components used may have an associated stray capacitance effect which is proportional to their resistance values. This is one reason why such operational amplifier circuits do not readily make it possible to obtain very high impedances within a wide frequency band.

It is also conventional to attempt to increase the apparent input impedance of an amplifier circuit of a given gain g and input resistance R by means of a feedback loop comprising in general a resistor and a capacitor connected in parallel between the output of the amplifier circuit and the upstream side of the circuit input resistor. Through a suitable choice of the resistance and capacitance values of the feedback loop components and of the gain of the amplifier, it is possible to maximize the value of the apparent input impedance, which can accordingly reach very high values. However, it had heretofore not appeared possible to devise very high input impedance amplifiers allowing the suitable transmission of AC as well as DC signal voltages. One reason for this is that low drift requirements, essential for reliable DC transmission, and wide passband requirements, are difficult to reconcile. Thus, most of the high impedance input circuits proposed up to the present time to operate from high impedance sources which are not capable of delivering a usable output, and in particular for the analog-to-digital converters used in voltage measurements for example, were altogether different in their design depending on whether or not DC voltage transmission was involved; for DC, in particular, the technique of chopper type amplifiers is most universally used.

One known means of attempting to overcome this difficulty with operational amplifiers is the Goldberg circuit. In this circuit, the applied input signal is highly filtered and its high-frequency component is capacitively coupled to a first input of a differential amplifier, generally provided with a negative feedback, while the low-frequency part of the signal, including the drifts of the differential amplifier, is direct coupled to a modulator, AC-amplifier, demodulator assembly whose output is direct connected to the second input of the differential amplifier. This assembly, which has a negative gain, corrects the output drift of the differential amplifier.

This kind of circuit, however, has various drawbacks, in particular for applications in the field of measurements. Among these drawbacks, are a circuit input impedance which varies according to frequency and

which is relatively low for low frequencies, poor transmission of AC series mode voltages and a long DC response time.

In order to overcome the above-mentioned disadvantages, it has been proposed (see, for example, an article by J.R. Jordan, "Positive Feedback Raises Open Loop Gain of Operational Amplifiers" which appeared in the British review *CONTROL*, Volume 11, No. 106, pages 164-167) that an input circuit be used having, as illustrated schematically in FIG. 1, two series-connected operational amplifiers A_1 and A_2 inverter mounted between two terminals α and β . A voltage source is shown schematically by a generator V_e and a resistor R_e , series-connected between ground and the α terminal. The first operational amplifier A_1 is preceded by an input resistor R_1 connected downstream of the terminal α to one of its inputs E_{11} having a "-" sign. This input E_{12} of this amplifier, having a "+" sign, is connected to ground across a compensating resistor R_6 . Between the output S_1 of the amplifier A_1 and its input E_{11} , a resistor R_2 is negative-feedback connected. The output S_1 is also connected, across a resistor R_3 , to a "-" input E_{21} of the amplifier A_2 . The other input E_{22} of this amplifier, having a "+" sign, is grounded across the compensating resistor R_7 . Between the output S_2 , connected to the terminal β , and the input E_{21} of the amplifier A_2 a resistor R_4 is negative-feedback connected. Finally, a positive feedback loop, of resistor R_5 , marked BR , is connected between the input terminals α and β respectively.

As the closed-loop gains of the amplifiers A_1 and A_2 are respectively R_2/R_1 and R_4/R_3 , the gain g of the equivalent amplifier is $g = R_2/R_1 \cdot R_4/R_3$. It is easily demonstrated that if the condition $g = 1 - R_5/R_1$ is satisfied, the input current of the circuit is zero at all times. It is thus sufficient for the values of the resistors R_1 , R_2 , R_3 , R_4 and R_5 to be chosen so as to comply, at least in an approximate manner, with the relationship $R_2/R_1 \cdot R_4/R_3 = R_5/R_1 + 1$, so that the apparent input resistance of the circuit has an infinite value or, at least, a value sufficiently high so that in no case does the operation of the circuit disturb the signals delivered by the voltage source.

It is immediately apparent that this circuit allows very high apparent input resistances to be obtained with components having relatively low resistances, and whose stray capacitances are consequently also low. The apparent input impedance of the circuit can thus be very high within a very wide passband. However, the mounting of two inverting amplifiers with a negative feedback makes it possible to minimize the influence of their input capacitance, because only a fraction of this capacitance appears at their output. In addition to its very high input impedance and its broad passband, this circuit offers the essential advantage of common-mode rejection at the input. The series connection of the two amplifiers in fact makes it possible, at least virtually, to keep all their inputs at a potential close to zero, so that the circuit can directly admit voltages sometimes as high as several tens of volts without requiring the use of an attenuator which would lower the system's dynamic input range. Finally, it is evident that the absence of filters makes it possible to obtain a practically negligible DC response time.

Such a circuit however has the disadvantage of not possessing any means of compensating for DC drift,

thereby making it unsuitable for use as an input circuit in high performance equipment.

To remedy this shortcoming, the present invention provides a high impedance circuit, of the type described, but whose operating stability is maintained under substantially all circumstances thanks to additional arrangements which are added to the circuit, according to whether it must transmit DC or AC signals.

An object of the invention is to provide a very high impedance circuit, comprising an amplifier of positive gain g and including a first and second operational amplifier, each inverter-connected with a resistive negative feedback and cascade-coupled, so that their inputs are substantially and at least virtually grounded, an input resistor of value R_1 , one terminal of which is connected to the input of the first operational amplifier, and a resistor of value R_5 , positive-feedback connected between the output of the second amplifier and the other terminal of the input resistor, the relationship $g=1+R_5/R_1$ being substantially verified so as to make the apparent input impedance of the amplifier almost infinite. The circuit also comprises, associated with the said operational amplifiers, in combination, a first means of drift stability control including a capacitor C inserted in the loop formed by the two operational amplifiers and the positive-feedback resistor, so as to open the said loop for drift signals having a frequency lower than that of the signals applied at the input, and a second means of drift stability control including at least one circuit made up of a voltage amplifier negative-feedback connected between the output of the second operational amplifier and an input of the first operational amplifier, a switching device designed to isolate this amplifier and operating in opposition with a switching device designed to apply the input signals intermittently, and a storage capacitor one terminal of which is brought to a reference potential and the other terminal of which is connected both to the output of the error voltage amplifier and to the said input of the first operational amplifier, the said first and second means being alternately made inoperative by switches according to whether the input signals are respectively of the DC or AC type.

Thus, when the input circuit has to transmit only pure AC voltages, its operating stability is maintained by the presence of the capacitor C thanks to which the error voltages, which may appear at the terminals of the negative-feedback resistor due to the offset voltages and currents of the first operational amplifier, cannot react, owing to their low frequency, through the said resistor or disturb the transmitted AC signals. When the signals to be transmitted possess a DC component, the operating stability is maintained by the second control means which, during each period that the input is disconnected from the source, detects the error voltage which may appear at the output of the circuit. A compensation voltage is then applied to the first operational amplifier to cancel this error voltage so that the circuit is automatically reset. This compensation voltage is also stored in the storage capacitor and can thus ensure the correction of the input signals during the following active period during which the input is again connected to the source.

Further, in accordance with the invention, the above mentioned second control means may include a circuit which comprises a storage capacitor connected in series between the input switching device and the up-

stream connection point of the negative-feedback resistor, and a switching device operating in opposition with the said input switching device and connected at an intermediate point between this device and the said storage capacitor. This additional arrangement also ensures the stability of the circuit by performing, outside of the active phases, the detection of error signals which may appear at the input of the circuit. These signals are used to charge the storage capacitor which, at each active phase, corrects the applied input voltage by the detected error voltage.

The invention will be better understood upon consideration of the following description of a particular embodiment of the circuit and with reference to the accompanying drawings in which:

FIG. 1 represents an input circuit according to the prior art, as previously described;

FIG. 2 represents an input circuit according to the invention;

FIG. 2A shows an additional embodiment according to the invention; and

FIG. 3 shows a curve of voltage variation at the input of the first operational amplifier of FIG. 2.

The very high impedance input circuit according to the invention, as shown in FIG. 2, includes all the elements of the circuit of FIG. 1, and is assigned the same reference numbers, but is characterized by the additional presence of the following elements:

an input switch I_e ;

a capacitor C connected between the output S_1 of the amplifier A_1 and the resistor R_3 . This capacitor may be short-circuited by a connection L provided with a switch I_L ;

an input signal correction circuit CE , delimited by a broken-line frame, and connected between the switch I_e and the terminal α ;

an output signal correction circuit CS , delimited by a broken-line frame, and connected between the output S_2 of the amplifier A_2 and via the resistor R_6 to the input E_{12} of the amplifier A_1 ;

a switch I' connected between ground and the input E_{12} of the amplifier A_1 .

In the FIG. 2 circuit, the values of the compensating resistors R_6 , on the input E_{12} of the amplifier A_1 , and R_7 , on the input E_{22} of the amplifier A_2 , are respectively:

$$R_2 (R_1 + R_5)/R_1 + R_2 + R_5 \quad \text{and} \quad R_3 R_4/R_3 + R_4$$

which ensures the best possible balancing of the said inputs.

It is important to note that the relationship $R_2/R_1 R_4 R_1 R_3 = R_5/R_1 + 1$ can only be satisfied to within the accuracy and the stability limits of the resistors with respect to time. This relationship is thus written in practice as follows:

$$R_5/R_1 \times 1/g - 1 = 1 \pm 1/K$$

With components of current quality, the value of the coefficient K is of the order of 10^4 . Under these conditions, instead of being infinite, the apparent input resistance of the circuit becomes equal to $(K \pm 1) R_1 \approx KR_1$, or $K R_5/g - 1$. The apparent input resistance is thus substantially equal to K times the order of magnitude of the resistances of R_1 and R_5 . According to the invention, one uses resistors R_1 and R_5 of the same value, thereby leading to a gain g equal to 2. For example, with resistances R_1 and R_5 of 100 kilohms and a coeffi-

cient K of the order of 10^4 , the apparent input resistance is equal to 100 Megohms, which is largely sufficient to prevent the operation of the input circuit from disturbing the signals to be transmitted.

When the signal delivered by the source V_e , R_e is pure AC, the selector switch I_e and the switch I' may be left constantly closed and the switch I constantly open; so that the voltage delivered by the source is admitted to the terminal α after having gone without alteration through the error signal correction circuit CE as will be explained below. It has been observed, and this constitutes a valuable aspect of the present input circuit, that the presence of the capacitor C in the circuit loop path was sufficient to assure the stability of its operation.

The capacitor C allows the signal to pass towards β while the output signal correction circuit CS remains inoperative as will be explained below. The error voltages which may appear at the terminal α and β owing to the offset currents and voltages of the amplifiers A_1 and A_2 do not, because of their low frequency, react through the loop BR nor disturb the AC signal transmitted through the input circuit. The capacitor C in fact opens the feedback loop between the terminals α and β for very low frequencies. The capacitor C could be connected at any other point between α and β , and for example, downstream of R_3 , or in series with R_5 on the loop BR , provided only that the frequency spectrum of the signal to be transmitted is outside of the range within which this capacitor C opens the loop. Thus, for example, with an AC signal whose lowest frequency is 30 Hertz, the circuit is in open loop for the noises and drifts whose frequency does not exceed 1 Hertz, thanks to the action of the capacitor C of 33 μF and a resistor of 100 $K\Omega$. The circuit remains stable and the transmission of the picked up signal is then excellent. Such an input circuit may be used advantageously with a digital voltmeter.

When the signal to be transmitted has a DC component, it is no longer possible to allow the action of the capacitor C ; it is short-circuited by closing the switch I and by opening the switch I' . The correction circuits CS and CE make it possible to carry out the controls and the compensations necessary for the stability of the circuit, in place of the capacitor C , in particular when the input signal handling circuit connected downstream of the system operates in an intermittent manner. An example of such a circuit is a dual-slope digital voltmeter, such as the one described in the French Pat. NO. 1,444,343 filed on June 8, 1965. In DC, this type of voltmeter picks up the input signal only intermittently during a given integration period, following which it is temporarily disconnected from the source, while a reference voltage of opposite sign is used to bring the integrator to the original potential.

The circuits CE and CS perform a detection and a compensation of an error signal during the periods when the input signal is not applied to the input circuit. Two error voltages are thus connected: on the one hand, the error voltage appearing at the output of the input circuit, by means of the output voltage correction circuit CS ; and, on the other hand, the error voltage appearing on the terminal α , by means of the circuit CE .

The circuit CS is composed essentially of a differential amplifier A_3 , associated with a capacitor C_3 . The amplifier A_3 is negative feedback connected between the output S_2 of the amplifier A_2 and the input E_{12} of

the amplifier A_1 . For this purpose, the output S_2 of the amplifier A_2 is connected to an input E_{31} of the differential amplifier A_3 bearing a + sign. A change-over switch I_{33} is inserted on the preceding connection. The input E_{31} is grounded upstream of the connection point 39 of the change-over switch I_{33} across a resistor R_{37} . The other input E_{32} of the amplifier A_3 , having a - sign, is also grounded across a resistor R_{38} equal in value to resistor R_{37} . The amplifier A_3 is equipped with a zero adjustment device RZ by means of which it is possible to cancel the output voltage S_3 at the beginning of utilization when the change-over switch I_{33} is open. The output S_3 of the amplifier A_3 is connected, via a change-over switch I_{34} and a connecting terminal 36, to a plate of a capacitor C_3 whose other plate is grounded at the point 35, and to the input E_{12} of the amplifier A_1 through the compensation resistor.

The negative feedback loop in which is situated the amplifier A_3 assures compensation for the drifts of amplifiers A_1 and A_2 even when the input signal is DC. For this purpose, the change-over 33 and I_{34} operate in phase opposition in relation to the input switch I_e : when this switch is closed, I_{33} and I_{34} are open, and vice versa. When the input circuit is disconnected in relation to the source, any residual voltage on the terminal β is transmitted to the input of the differential amplifier A_3 which delivers a compensation voltage and reacts on the input E_{12} of the amplifier A_1 so as to cancel the error signal at the output of the circuit or, more precisely, to bring to a value lower than the resolution of this circuit. At the same time, the compensation voltage delivered by the amplifier A_3 is stored by the capacitor C_3 . Thus, the zero of the input circuit is automatically reset during the rest period of the measurement instrument. When I_e is closed, I_{33} and I_{34} open simultaneously under the action of a control device, not shown, thereby isolating the differential amplifier A_3 in relation to the input circuit. The compensation voltage stored by the capacitor C_3 assures the correction of the input signal during the active phase.

It is to be noted that, if the input circuit is followed by another amplifier, for example a variable gain amplifier 50, it is preferable to connect the input E_{31} of the amplifier A_3 to its output in order to correct its drift with respect to time and temperature.

The compensation performed at the level of the input E_{12} of the amplifier A_1 by the circuit CS takes into account the drifts of the two amplifiers A_1 and A_2 but does not prevent the appearance of any error voltage ϵ_1 when the terminal α is disconnected (switch I_e open). This voltage may in particular result from the offset current of A_1 flowing in the loop BR , and the role of the circuit CE is to get rid of it.

This circuit is composed essentially of a capacitor C_4 connected in series between the change-over switch I_e and the terminal α ; a change-over switch I_4 connected between the upstream terminal 40 of this capacitor C_4 and ground, and operating in opposition with I_e , forms a series-parallel chopping circuit with I_e . These switches, and these of the circuit CS , may consist of field effect transistors, for example. When the switch I_e opens, the terminal α is automatically grounded through I_4 via the capacitor C_4 which is then charged at the error voltage ϵ_1 . When I_e closes, I_4 opens and the input voltage V_e is immediately transmitted to the terminal α through the capacitor C_4 which corrects V_e by the error voltage ϵ_1 present at α ; the input current is

practically zero. It is noted that the operation of this input circuit does not require the charge of the capacitor C_4 , and a very short DC response time is thus obtained. Quite the contrary, an attempt is made to prevent the charge of the capacitor C_4 from disturbing the value of the voltage admitted at the terminal α of the input circuit. To accomplish this, the capacitance of C_4 is calculated as a function of the time Δt during which the switch I_e remains closed so that the voltage variation at α is smaller than the resolution of the system. If ΔV is this resolution, then the previously expressed condition may be written

$$\Delta t / K R_1 \times V_e / C_4 < \Delta V$$

FIG. 3 shows the variation of the voltage V_α at the point α as of the instant of closing of I_e as a function of time t . The variation ΔV_α of the voltage V_α during the time Δt has been indicated on this curve. The chopping time Δt is related to the operating time of the system located downstream of the circuit. In fact, in order to prevent low level switching during this operating time or measuring time, the switch I_e is controlled such that the input signal is always applied before the beginning of the measuring time, and interrupted when the measuring time has elapsed. However, the above condition is relatively easy to satisfy because the quantity $1/KR_1$ is very small owing to the very high apparent input impedance KR_1 of the circuit.

As indicated earlier, the impedance of this circuit is considerable and remains so, as does its gain, within a wide passband. There is no chopping during the measuring period, thus contributing to the quality of the input signal transmission. The signal picked up during the measuring time is not modulated. The series mode AC voltages are transmitted through the circuit. Moreover, the DC response time is very short, in particular compared with prior art input amplifiers having filters with a significant time constant.

Finally, whether for pure AC, or for DC signals, the stability of the circuit is controlled by simple additional devices which also make it possible to correct the effects of amplifier drift with respect to time and with temperature variations.

With an input circuit in accordance with the preceding principles, an input resistance of 1,000 megohms was obtained with an input capacitance of 20 picofarads between 1 Hertz and 100 Hertz, the transmission of the input voltage being achieved with an accuracy higher than 10^{-3} . Such input circuits have been embodied in the form of plug-in units used specifically for the transmission of either DC or AC, or, as in the foregoing description, in the form of universal units.

What is claimed is:

1. A very high impedance input circuit, comprising: an amplifier of positive gain g composed of first and second dual input operational amplifiers, each of said amplifiers being inverter-connected with a resistive negative feedback and said amplifiers being cascade coupled so that their inputs are substantially at virtual ground;
2. an input resistor of value R_1 , one terminal of which is connected to one input of the first operational amplifier;
3. a resistor of value R_s positive-feedback connected between the output of the second operational am-

plifier and the when input signals are coupled to said first operational amplifier, said voltage amplifier is isolated from said first and second operational amplifiers; and

a second storage capacitor one terminal of which is connected to a reference potential and the other terminal of which is coupled to the junction of said means for coupling and said first switching means.

2. An input circuit according to claim 1 wherein said second switching means operates to continuously couple applied AC signals and intermittently couple applied DC signals to the one input of said first operational amplifier.
3. An input circuit according to claim 2 further including,

a third capacitor connected in series circuit relationship with said second switching means and said input resistor R_1 , and a third switching means operating in phase opposition with said second switching means and connected to a point between said second switching means and said capacitor.

4. An input circuit according to claim 3 wherein the capacitance of said second capacitor is determined as a function of the period during which said second switching means provides an input signal coupling path to said input circuit such that the potential variation at the terminals of said second capacitor during this period is lower than the resolution of the system.

5. An input circuit according to claim 1 and further including:

a variable gain amplifier having an input connected to the output of the input circuit and having an output other terminal of the input resistor, so as to establish the relationship $g = 1 + R_s/R_1$ and to make the apparent input impedance of the amplifier practically infinite, the circuit further comprising in association with said operational amplifiers;

a first means of drift stability control including a first capacitor inserted in the loop formed by the two operational amplifiers and the positive feedback resistor for opening said loop for drift signals having a frequency lower than that of signals applied to the input circuit;

a second means of drift stability control including at least one circuit including a negative-feedback voltage amplifier having an input terminal connected to the output of the second operational amplifier;

a first switching means connected to said voltage amplifier for decoupling said voltage amplifier from said first and second operational amplifiers;

means connected to said first switching means for coupling the output of said voltage amplifier to said other input of the first operational amplifier;

a second switching means for coupling input signals to said one input of said first operational amplifier;

means for operating said first and second switching means in phase opposition to one another such that connected to said input of said second means of drift stability control, switching means operative with said first switching means for decoupling said voltage amplifier from said variable gain amplifier, the output of said variable gain amplifier being further connectable to a utilization device.
